UNITED STATES PATENT OFFICE.

WILLIAM DALTON, OF SCHENECTADY, NEW YORK.

ARMOR-PIERCING SHELL.

Application filed November 18, 1921. Serial No. 516,180.

To all whom it may concern:

Be it known that I, WILLIAM DALTON, a citizen of the United States, residing at Schenectady, in the county of Schenectady 5 and State of New York, have invented certain new and useful Improvements in Armor-Piercing Shells; and I do hereby declare the following to be a full, clear, and exact description of the same, reference being had to the accompanying drawings, forming part of this specification.

This invention relates to an armor piercing shell and particularly to the base thereof and the shape of the bandscore.

15 The object of the present invention is to so fashion a shell base for an armor piercing shell that when the shell strikes a plate of armor at an appreciable angle, say ten to twenty degrees from normal, the shell 20 will be able to penetrate the armor without disrupting in any way the wall of the inner cavity of the shell.

Should the wall of the inner explosive-carrying cavity be injured even by a slight 25 crack the explosion of the shell would be comparatively ineffective. Many tests of shells fired so as to strike the armor at an angle other than practically normal seem to indicate that there is a great friction at 30 the outer surface near the base as this portion is very frequently severely scored and it is not at all unusual to find a shell wedged in the hole of the armor by its base with a subsequent cracking of the wall of the explosive chamber.

35 It is my belief that the cracking of the wall of the explosive chamber could be avoided by the provision of a line of weakness following a curve around the base of the shell and experiments have already been tried which seem to verify this belief. The previous designs to accomplish this end have unfortunately required what seems to be an excessive amount of additional cost of the 40 shell, such structures as I am familiar with requiring a large amount of machining and calling for a number of hours of labor of the most skillful and highest paid type.

45 It is an object of the present invention therefore to obtain a shell having as many of the advantages as possible of these experimental types but which can be produced at a materially lower cost.

In the drawings,—

55 Figure 1 is a vertical section through a

standard shell modified in accordance with the present invention.

Fig. 2 is a fragmentary view similar to the view in Fig. 1 but on a considerably greater scale.

60 Figs. 3, 4, 5 and 6 are views similar to Fig. 2 but showing modifications of the retaining ring.

Figs. 7, 8 and 9 are further modifications.

65 The shell consists of a body portion 10 having a central chamber 11 adapted to carry the explosive charge and having a threaded base plug 12 forming the rear wall of the explosive chamber, such base plug having the usual fuse hole plug 14 screwed 70 therein. This armor piercing shell being of the usual type has the customary cap 15 and the hollow piece 16 forming the so-called nose piece and acting as a windshield but adapted to crush and be totally destroyed upon impact with the armor.

75 The rotating band 17 may be of the usual configuration on its outer face but varies from the usual practice in that it fits the peculiarly shaped bandscore shown in Fig. 80 2. The greater or side face 18 of the bandscore is of conical shape, the metal of the shell decreasing in diameter from the upper apex 19 to the point 20. The upper face 21 of the bandscore is also conical and preferably forms an acute angle in cross section with the cylindrical surface 22 of the body and consequently forms an acute angle with the side 18 as well. While the formation of this acute angle is found to be extremely 85 90 advantageous it is not known to be absolutely essential and I do not care to have the scope of the invention limited to the exact construction as shown.

95 The reduced portion of the shell body is practically cylindrical from the point 20 to the point 23 on the base but the lower end of the shell is threaded as at 24 to receive an annular retaining ring 25 which may carry a basescore 26 to receive the standard 100 naval base cover (not shown). An inward extending weakening groove 27 is cut in this reduced cylindrical portion of the shell at a point just above the threads 24 and somewhat below the point 20 in order to direct 105 the line of fracture away from the upper portion of the threaded base plug and preferably to the edge 28 of the extended flange of such plug and for this reason the upper surface 30 of the weakening groove 27 is 110

directed at an angle of about 45° with the axis or with the base and the lower surface 31 of the groove is either directed downward to the outer rim of the plug, or may, as illustrated, be made parallel with the shell base for convenience in manufacturing.

The upper surface 33 of the retaining ring is also of conical shape, the outer edge 34 of the surface being appreciably further from the base than is the point 20 so that the surface 33 forms an acute angle in cross section with the side face of the bandscore; the latter, in the embodiment illustrated, having each of its faces tapered or conical, the smaller upper face 21 forming an undercut with the shell body and the other end face 33 likewise forming an acute angle with the cylindrical portion of the body as well as with the side face of the bandscore.

In previous experimental types of armor piercing shell the excessive cost was due to the great quantity of machining of the ring required and the fitting had to be perfect owing to the fact that after the ring is applied to the shell the nicks are then placed in the bandscore which operation has a tendency to increase the diameter of the ring which will naturally recede from the shell body and therefore cause a loose fitting of the forward part of the ring.

In the present device it is my belief that any variation in the machining of the bandscore or of the copper band will be compensated for during the application of the band by its shrinkage. The band will be applied to the shell and then the master base ring 25 will be screwed on to hold the band in position and then the body and ring will be tapped to receive the locking screw 36 after which the shell with the band applied will be placed in the hydraulic press and the band seated only enough for the nicking to show a good photograph.

It will thus be seen that the copper band may be fitted to the shell without any heating or swedging, the operation merely consisting in the forcing of the copper on the taper fit and holding it with a retaining ring which is screwed tight against the copper band and held in the manner stated or by burring the thread or by peening over.

In the modifications shown in Figs. 3, 4 and 5 the retaining ring is secured to the shell by means other than by threaded engagement. In Fig. 3 the ring 40 is shrunk on the shell and is further secured by the screws 41. In Fig. 4 the band is applied hot and the ring 42 is forged on the shell, which in this modification has a base flange 44 so that the forged ring 42 lies in an annular groove 45 bounded by the annular face 46, and the upper face 47 of the flange. The ring 49 of Fig. 5 is quite similar,

but in this modification the band is intended to be applied cold and for this reason the diameter of the flange 50 is less than the minimum diameter of the band to allow the latter to pass, and hence the groove 51 in the shell is bounded by faces 52 and 53 of approximately equal depths.

In Fig. 6, the greater face 60 of the bandscore extends from the upper face 61 to the base, being entirely conical, the retaining ring 62 in this modification having an outer cylindrical surface 63 and an inner conical surface 64. The ring 62 is pressed on and is held in place by a plurality of screws 65 which not only prevent the band from rotating but also prevent the band from coming off the shell body until the shell goes through the armor plate.

In Figs. 7 to 9 a somewhat modified form of shell is illustrated, the principal difference being that the central chamber is so formed that the diameter of the mouth of the opening is appreciably less than the greatest diameter of this chamber which holds the explosive charge. In other words, the central chamber increases in diameter from the entrance to its greatest swell and then decreases in the direction of the point of the shell in the usual manner. The base plug 72 is consequently appreciably smaller in diameter than the corresponding plug 12 of Figures 1 to 5, and the thickness of the shell is therefore least at the point 73 above the top of the band instead of at a point lower than the top of the band as in the remaining figures. The design of the explosive charge chamber shown in Figs. 7 to 9 strengthens the shell to a considerable degree as there is no reentrant angle at the point of minimum thickness, and the tendency to crack through or break at the point 73 is slight.

In these three figures the bandscore has but two sides, the short upper side and the major face of the bandscore which is conical and extends to the bottom of the shell. A steel retaining ring is shown in each of these three figures and a plurality of pins or studs engage the ring, the copper band and the main body of the shell, the construction in Fig. 9 for example being very similar to that shown in Fig. 6, save for the shape or cross-sectional contour of the central chamber.

In Fig. 7 the copper band 75 extends entirely to the base of the shell and has at its lower end an angular groove bounded at the top by a short face 76 forming a shoulder and a cylindrical or conical side face 77. The steel retaining ring 78 fits within this groove with a shrinkage fit and has an upper dished conical face, and a rounded lower corner 79, and is secured in place by a plurality, preferably four, of

pins 80 which extend entirely through the ring 78 and the band 75 and into the steel shell.

As an additional security a plurality of 5 dowels 82, approximately three-eighths of an inch by three-sixteenths of an inch for a 14-inch shell for example, are provided located as shown in the figure. The copper band 75 is secured in place with a force fit, 10 the steel ring is then shrunken on, the taps made and the pins 80 and the dowels 82 inserted. The shell just described is preferred for many purposes and its design 15 reduces very largely the cost of manufacture, the major face 84 of the bandscore being unthreaded and the smaller upper face 85 of the bandscore being similar to the corresponding faces 21 and 61.

In Fig. 8 the greater portion of the major 20 face 86 of the bandscore is provided with left hand threads as at 87 and the copper ring is screwed in place on these threads and is provided with a steel ring 78 similar to that shown in Fig. 7. It will be noted that 25 the only difference between the structures shown in Figs. 7 and 8 is the substitution of the threads 87 for the dowels 82. It might also be remarked that the use of the threads allows for the use of a lesser number of pins, three being found ample in a shell of the type shown in Fig. 8.

The shell shown in Fig. 9 is very similar 30 to that shown in Fig. 6 save that the ring 88 is somewhat taller and thinner than the corresponding ring 62 and the studs 89 are therefore somewhat longer than the similar 35 studs 65. The shape of the copper rotating band unnumbered in each of these two figures is somewhat different but it will be understood that these bands are equivalents 40 in the same way that the shape of the ammunition or explosive chamber are equivalents.

What is claimed is:

45 1. A shell body having a tapered portion forming with the cylindrical portion of said shell an annular shoulder, a substantially cylindrical portion forming the lower end of said shell body and merging with 50 the smaller end of said tapered portion, a weakening groove located in the upper part of said cylindrical portion, and means adapted to be secured to said lower cylindrical end to form with said shoulder and

55 said tapered portion a bandscore and also serving to close the open end of said weakening groove.

2. In combination, a shell having a reduced portion at its lower end thus forming 60 a shoulder, a retaining ring adapted to be secured to the reduced portion of said shell to form with it a second shoulder, these two shoulders forming the end faces of a bandscore, the shell body having a weakening groove therein underlying the ring whereby 65 said ring may be torn from the shell with a small portion of the rear rim of the shell body when penetrating armor.

3. In combination, a band having a conical inner face, a shell having an integral 70 portion forming the side face of a bandscore, the angle of said side face corresponding to the angle of said conical inner face, and means adapted to be secured to said shell to engage said band and to form an 75 end face for said bandscore, the shell body having a weakening groove therein underlying said band retaining means whereby said means may be torn from the rear rim 80 of the shell body when penetrating armor.

4. An armor piercing shell characterized 85 by the provision of a tapered side face of the bandscore, an inward directed weakening groove in the shell body below the lower end of said bandscore, and a retaining ring 90 adapted to be secured to the lower end of said shell body, to form with said groove an annular cavity, and to form the lower face of the bandscore.

5. In an armor piercing shell, a shell 95 body having a frusto-conical portion at its lower end, said frusto-conical portion meeting the main body of the shell in an undercut, a substantially cylindrical extension below said frusto-conical portion and having 100 cut therein an inward extending weakening groove, threads below said groove, a retaining ring threaded to fit said cylindrical extension and having a conical upper face, a rotating band adapted to fit in said undercut at its upper end, against said frusto-conical portion on its inner face and against the conical portion of said retaining ring at its lower end, and means for preventing 105 relative movement between said retaining ring and said shell body.

WILLIAM DALTON.
